DESIGN FOR A KNOB FOR KITCHEN
UTENSILS

Richard F. Krause, Massillon, Ohio, assignor to
The Enterprise Aluminum Company, Massillon,
Ohio, a corporation of Ohio

Application October 2, 1946, Serial No. 133,700

Term of patent 7 years

(Cl. D44—29)

To all whom it may concern:

Be it known that I, Richard F. Krause, a citizen of the United States, residing at Massillon, in the county of Stark and State of Ohio, have invented a new, original, and ornamental Design for Knob for Kitchen Utensils, of which the following is a specification, reference being had to the accompanying drawing, forming part thereof.

Fig. 1 is a top plan view of a knob for kitchen utensils showing my new design;

Fig. 2 is a side elevation of the knob shown in Fig. 1;

Fig. 3 is a bottom plan view of the knob shown in Figs. 1 and 2; and,

Fig. 4 is a vertical sectional view through the knob shown in Figs. 1, 2 and 3.

I claim:

The ornamental design for a knob for kitchen utensils, substantially as shown.

RICHARD F. KRAUSE.
